UNITED STATES PATENT OFFICE.

CHARLES L. THATCHER, OF PROVIDENCE, RHODE ISLAND, ASSIGNOR TO IRONS AND RUSSELL COMPANY, OF PROVIDENCE, RHODE ISLAND, A CORPORATION OF MAINE.

BUTTON.

1,104,084.

Specification of Letters Patent. Patented July 21, 1914.

Application filed March 12, 1914. Serial No. 824,226.

To all whom it may concern:

Be it known that I, CHARLES L. THATCHER, a citizen of the United States, and resident of the city of Providence, in the county of Providence and State of Rhode Island, have invented certain new and useful Improvements in Buttons, of which the following is a specification.

This invention relates to buttons of the 10 class adapted to be readily attached to and detached from the button-hole in the coat of the wearer, and the object of this invention is to provide a button having a front plate which may be ornamental or contain some 15 emblem, or the like, and provide the same with a central buttonhole engaging post to which a lever or locking member is pivotally connected, said member having portions extending on opposite sides of the pivoting 20 point and adapted to be turned up substantially in line with the post to facilitate passing through the buttonhole and subsequently to be turned down at substantially right angles to the post to engage the back side of 25 the fabric and lock the button in position.

A further object of the invention is to pivot the lever member to the post with its pivoting axis substantially in line with the reading matter on the front of the button, 30 whereby to position the button in the hole it is first turned a quarter turn from its normal reading position and when turned back the pair of gripping fingers on said lever engage the fabric on opposite sides of the 35 buttonhole to firmly retain the button in position on the garment.

One of the features of this invention is that the back or attaching portion of the button is connected permanently to the front 40 so that the parts cannot be separated and lost.

With these and other objects in view, the invention consists of certain novel features of construction, as will be more fully described and particularly pointed out in the 45 appended claims.

Of the accompanying drawings: Figure 1 is a view showing the back of the button in 50 position for locking the button in the buttonhole of the coat. Fig. 2 is a plan view showing the shape of the lever member as struck from sheet stock. Fig. 3 shows the shape of the lever member having its joint arms bent up in position and engaging the 55 pivot on the post. Fig. 4 shows the lever

member pivotally connected to the button post and turned up in line with said post. Fig. 5 shows the lever member as tipped down at right angles to the post showing the same in position to engage the fabric on 60 each side of the pivoting point and grip the same against the back of the front plate. Fig. 6 shows the front button plate and post with its pivoting pintle formed thereon. Fig. 7 shows the relation between the reading matter on the emblem and the axis of 65 the pivoting pintle. Fig. 8 is a view showing the lever member in the position in which the button is most readily adapted to be turned at right angles after having been 70 positioned in the buttonhole and before it is turned back into position to grip the fabric.

Referring to the drawing, 10 designates the front plate of the button which may be in any desired shape or form, and which 75 may carry on its face any suitable ornament or emblem. On the back of the button is a post 11 which may be secured thereto by solder or other suitable means. This post is provided with a pintle 12 preferably 80 formed integral therewith and the axis of this pintle is preferably set in line with the reading matter on the button face so that when the button is in proper position in the buttonhole the axis of the pintle will be upright, in other words, the axis of the pintle 85 will be at right angles to the buttonhole through which the post extends.

The lever member 13 is preferably struck from a piece of sheet stock into the form best illustrated in Fig. 2 having two middle spaced apart parallel fingers 14 and two edge binding fingers 15. The next operation is to bend the whole member into substantially the form illustrated in Fig. 5, the 90 fingers 14 being raised, and bent or folded around the pivot 12 on the post 11, the ends of the fingers 15 being turned slightly downward so as to engage, grip and bind the fabric *a*, while the operating portion 16 on the 95 side of the pivot opposite to that of the fingers 15, is bent downward so that the portion 17 will rest upon the fabric and the extremity will stand slightly upward to be engaged by the thumb and finger of the wearer when 100 it is desired to manipulate the same. By 105 this construction it will be noted that the fingers 15 extend to one side of the pivoting point and the portion 16 on the opposite side thereof so that after the lever has been 110

moved to locked position it is anchored and no pressure or pull on the front plate can cause the lever member to be moved to release position. By constructing the lever member in this way the extremities 18 of these fingers 15 are preferably slightly rounded so as to slide over the fabric when the lever is moved to engaging position after being passed through the button hole without catching into and injuring the nap or fibers of the fabric.

Another feature of my improved button is that the lever member may be turned up as illustrated in Fig. 4 substantially in line 15 with the post 11 so as to facilitate the passing of the same through the buttonhole in the coat of the wearer.

The operation of my improved button may be described as follows: The lever is 20 first turned up into the position illustrated in Fig. 4 and is passed through the button hole. The lever is then preferably turned into the position illustrated in Fig. 8 in which the little engaging fingers 15 extend 25 upward to permit the button to be readily turned in the buttonhole without these fingers engaging the fabric. After the button has been positioned so that the reading matter is in correct position the lever member 30 is then turned over into the position illustrated in Fig. 5 whereby the fingers 15 and the portion 17 of the lever engage and grip the fabric on opposite sides of the post binding the same firmly against the inner side of 35 the front plate and holding the button securely in position.

I claim:

1. A button comprising a front plate having a buttonhole engaging post, a retaining 40 member carried by said post having a pair of yieldable fabric engaging fingers the whole being adapted to be rotated a quarter turn after passing through the buttonhole and means whereby said fingers may be 45 moved to yieldably grip the fabric and bind the same against the back of the front plate.

2. A button of the character described comprising a front portion having a button-hole engaging post, a retaining member pivoted on said post and having portions extending on opposite sides of the pivoting point, said member being adapted to be turned up substantially in line with the post to facilitate passing through the buttonhole and subsequently to be turned down at substantially right angles thereto to engage the fabric and lock the button in position.

3. A button comprising a front plate having a buttonhole engaging post, a retaining member pivoted on said post and having one or more yieldable fabric engaging fingers extending to one side of the pivot, and a binding and manipulating portion on the other side of said pivot, said member being adapted to be turned up substantially in line 65 with the post to facilitate positioning in the buttonhole of the wearer and to be turned down on its post at substantially right angles thereto to lock the button in position.

4. A button comprising a front plate having a buttonhole engaging post, a retaining member pivoted on said post and having a pair of yieldable fabric engaging fingers extending to one side of the post, and a binding and manipulating portion on the 75 other side of said pivot, said member being adapted to be turned up substantially in line with the post to facilitate positioning in the buttonhole of the wearer, the whole being adapted to be rotated a quarter turn after 80 passing through the buttonhole and the retaining member then turned down at substantially right angles to the post to cause said fingers to yieldably grip the fabric and bind the same against the back of the front 85 plate.

In testimony whereof I affix my signature in presence of two witnesses.

CHARLES L. THATCHER.
